CYCLE SADDLE POST

Harold E. Kalter, Elyria, Ohio, assignor to The
Troxel Manufacturing Company, Elyria, Ohio,
a corporation of Ohio

Application February 27, 1939, Serial No. 258,743

5 Claims. (Cl. 287—14)

My invention relates to cycle saddles and relates more particularly to an improved construction for securing a saddle, such as a bicycle or motorcycle saddle, to the saddle post of the vehicle.

An object of my invention is to provide improved means for connecting the saddle to the saddle post.

Another object of my invention is to provide an improved construction of the type described which can be conveniently and inexpensively made and which will be more effective in performing the functions required of it than assemblies heretofore in use and with which I am familiar.

Another object of my invention is to reduce the number of parts required in assemblies of the type described.

A further object of my invention is to provide an improved assembly of the class described which can be adapted for use with variously formed vehicles and regardless of the degree of incline desired with respect to the saddle post.

Another object of my invention is to provide an improved assembly of the type described which will more effectively and securely hold said saddle post to the saddle structure.

Other objects of my invention and the invention itself will be better understood by reference to the drawing forming a part of this specification and in which drawing:

Fig. 1 is a longitudinal medial view of an embodiment of my invention;

Fig. 2 is a bottom plan view of said embodiment;

Fig. 3 is an end elevational view of the saddle post employed in my invention, said post being broken away at a midsection thereof;

Fig. 4 is a fragmentary sectional view of one of the reach bar members employed in my construction and taken from the plane 4—4 of Fig. 2.

Referring now to the drawing, in all of which like parts are designated by like reference characters:

At 1, I show a saddle post preferably formed from solid metal stock, although sheet metal or the like could be employed. The saddle post is of hook form and is provided with a post stem 2 and an eye portion 3. The eye portion of the post is knurled or grooved on its opposite side faces, preferably as shown in Fig. 3, wherein I have illustrated said eye as being provided with spaced substantially radially extending grooves with interposed ridges, although any indenturing of said surfaces which would render the same

rough might be employed. The saddle assembly, as shown in Figs. 1 and 2 herein, is of the conventional type having a saddle seat element 5 preferably comprising a sheet metal supporting frame to which the seat supporting means comprising supporting springs and a pair of reach bars 4 and 4' may be secured.

The reach bars in the present embodiment are in the form of a pair of generally parallel flat reach arms 4 and 4', secured to the front 10 and rear portions of the saddle supporting frame in any desired manner, such as that herein illustrated.

My invention is applicable to any saddle construction, it being merely necessary to provide a 15 pair of suitably formed clamping elements carried by the saddle or some part thereof, such as reach members, the seat frame, or the like, between which the indentured upper end 2 of the saddle post may be received, and between which it may be clamped.

In the embodiment illustrated, as a matter of economy in manufacture, the flat metal reach bands 4 and 4' have the inner opposing faces 8 and 9 of their intermediate portion provided with alternate ridges and depressions, as illustrated in Fig. 4, whereby said reach bands themselves function as clamping elements. No additional clamping elements, secured to said reach members, are required in the saddle construction herein disclosed.

However, in other saddle constructions, the clamping elements may take some such form as those illustrated in Figs. 4 and 5 of the prior Eckenroad Patent No. 1,147,007, dated July 20, 1915, and may be made separately from each other or may be interconnected by a resilient yoke, as will be well understood.

In the embodiment herein illustrated, the inner surfaces 8 and 9 of the clamping portions of the reach members contain alternate preferably substantially radially extending grooves and ridges, the ridges of which are adapted to fit within the substantially radial grooves indented in the eye of the post 1, Fig. 3, and vice versa.

A bolt 6 is then projected through aligned apertures of the clamping element portions of the two reach bands and the eye 3 of the saddle post, which is previously projected between the bands. 50 The bolt 6 preferably has its stem portion immediately adjacent the underside of its head made square, the perforation 10 through the associated band being made of similar form to receive the squared bolt portion, to prevent rota-

tion of the bolt when projected through the band.

A nut 7 on the end of the bolt projected through the opposite band, when tightened, presses the ridges, such as those shown at 17, of the post into correspondingly formed grooves on the opposing inner surface of the associated reach member, and vice versa, whereby a locked clamping engagement is effected between the reach members and the eye of the bolt.

10 The form and placement of the alternate grooves and ridges, both in the bolt eye and on the opposing surfaces of the clamping elements receiving said eye, ensure that the saddle seat will not become displaced from its proper rotational position with respect to the eye of the bolt, and permits the seat to be optionally adjusted to any of a plurality of relatively inclined positions, by merely loosening the nut 7, tilting the seat to the desired angle, and then 15 tightening the nut.

20 My invention is susceptible of numerous departures from the form and embodiment herein illustrated, but without departing from the spirit of the invention, or the scope of the appended claims.

I claim:

1. In a cycle saddle assembly, a pair of opposing clamping members, a saddle post having an eye at its upper end, said eye adapted to be projected between said opposing clamping members, the confronting faces of said members being indentured and the opposite faces of the eye being likewise indentured, means whereby said post is adapted to be clamped between said 35 clamping members.

2. In a cycle saddle assembly, a pair of opposed clamping members suspended from said saddle and secured thereto, a saddle post comprising a hook end and stem portion, said hook having indentured opposite faces, the confronting faces 40

of said clamping members being provided with cooperating indentured portions, said hook end of said post adapted to be projected between said indentured portions and to be clamped therewith.

3. In a cycle saddle assembly, a pair of longitudinally disposed reach members, a saddle post comprising a hook end and stem portion, said hook having indentured opposite faces, the confronting faces of said reach members being provided with cooperating indentured portions, said hook end of said post adapted to be projected between said indentured portions of said reach members and the indentured opposite faces of said post adapted to be clamped therewith. 15

4. In a cycle saddle assembly, a pair of longitudinally disposed reach members, a saddle post comprising a hook end and stem portion, said hook having indentured opposite faces, the confronting faces of said reach members being provided with cooperating indentured portions, said hook end of said post adapted to be projected between said indentured portions of said reach members and the indentured opposite faces of said post and to be maintained in locking engagement therewith. 20

5. In a cycle saddle assembly, a pair of opposed clamping members suspended from said saddle and secured thereto, a saddle post comprising a hook end and stem portion, said hook having 30 indentured opposite faces, the confronting faces of said clamping members being provided with cooperating indentured portions, said hook end of said post adapted to be projected between said indentured portions, means adapted to be projected through aligned perforations disposed in said clamping members and said hook portion and to clamp said members and post together. 35

HAROLD E. KALTER. 40
